UNITED STATES PATENT OFFICE

95,035

DESIGN FOR A JUG OR SIMILAR CONTAINER

John M. Gayner, Salem, N. J., assignor to Gayner Glass Works, Salem, N. J., a corporation of New Jersey

Application January 15, 1935, Serial No. 54,859

Term of patent 14 years

To all whom it may concern:

Be it known that John M. Gayner, a citizen of the United States, and a resident of Salem, in the county of Salem and State of New Jersey, has invented a new, original, and ornamental Design for a Jug or Similar Container, of which the following is a specification, reference being had to the accompanying drawing, in which:

Fig. 1 is an end view of my design.

Fig. 2 is a front view of Fig. 1.

Fig. 3 is a plan view of Fig. 1.

I claim:

The ornamental design for a jug or similar container, as shown.

JOHN M. GAYNER.
